DISPENSING CONTAINER FOR FACIAL TISSUES

Peter C. Carveth, Winfield, Ill., assignor to Container Corporation of America, Chicago, Ill., a corporation of Delaware

Filed Apr. 2, 1963, Ser. No. 74,264

Term of patent 14 years

(Cl. D52—2)

Fig. 1

The side opposite that shown in FIGURE 1 is substantially the same as the side shown and the rear is essentially plain and unornamented.

I claim:

The ornamental design for a dispensing container for facial tissues, as shown and described.
